UNITED STATES PATENT OFFICE.

JACUB SCHWARTZMAN, OF BROOKLYN, NEW YORK.

LINK FABRIC FOR BEDSPRINGS.

Application filed November 26, 1921. Serial No. 518,013.

To all whom it may concern:

Be it known that I, JACUB SCHWARTZMAN, a citizen of the United States, residing at Brooklyn, in the county of Kings and State 5 of New York, have invented certain new and useful Improvements in Link Fabrics for Bedsprings; and I do hereby declare the following to be a full, clear, and exact description of the invention, such as will enable others skilled in the art to which it appertains to make and use the same, reference being had to the accompanying drawings, and to characters of reference marked thereon, which form a part of this specification. 10 15

This invention relates generally to an improved construction of wire fabric, and novel link elements making up the same, adapted to provide a flexible yielding bed- 20 bottom or springs for beds, couches, and other furniture.

The invention has for its principal object to provide an improved wire fabric made up of interconnected novel link elements of 25 such construction, that the fabric may be very easily and quickly assembled out of said link elements, and when assembled the same produces a novel flexible fabric capable of resilient lateral stretch, which renders the fabric more readily capable of 30 accommodating itself yieldingly to the contour of the body of the person or persons lying on a bed or couch equipped therewith.

A further object of the invention is to 35 provide a novel construction of wire link element for bed-spring fabrics which is easily and rapidly formed, and which is of such construction that the number of bends necessary to its proper formation are reduced to a minimum, while at the same time a comparatively small amount of material 40 is required to make up a complete fabric due to the novel shaping of said link elements.

45 Other objects of this invention, not at this time more particularly enumerated, will be clearly understood from the following detailed description of the same.

With the various objects of this invention in view, the same consists, primarily, in the novel wire fabric and link elements therefor hereinafter set forth; and the invention consists, furthermore, in the novel arrangements and combinations of the several devices and parts, as well as in the details of the construction of the same, all

of which will be more fully described in the following specification, and then embodied in the claims appended thereto.

The invention is clearly illustrated in the accompanying drawings, in which:—

Figure 1 is a fragmentary plan view of a wire bed-spring fabric, illustrating one embodiment of the principles of this invention; Fig. 2 is a longitudinal section 65 through the same, taken on line 2—2 in Fig. 1; Fig. 3 is a fragmentary plan view of a modified form of wire bed-spring fabric also embodying the principles of this invention; and Fig. 4 is a longitudinal section 70 through the same, taken on line 4—4 in Fig. 3.

Similar characters of reference are employed in the above described views to indicate corresponding parts. 75

Referring now to the form of wire fabric illustrated in Figs. 1 and 2 of the drawings, the reference character 1 indicates a main or primary link element, which is formed from a single length of wire suitably bent 80 to produce a substantially M shape, comprising parallel longitudinally extending laterally spaced leg portions 2 integrally connected together at their upper ends by a lateral V-shaped portion 3. The junctions of the upper ends of said leg portions 2 with the outer ends of the intermediate V-shaped portion 3 provide rounded loop- 85 portions or seat portions 4. The free or lower extremities of said leg-portions 2 are 90 turned or bent back upon themselves to form eye-portions or hooks 5, disposed to extend in a plane at right angles to the general plane of the main or primary link element. 95

The reference character 6 indicates a secondary or connector link element, which is also formed from a single length of wire suitably bent to produce a small M shape, comprising parallel longitudinally extending laterally spaced leg portions 7 integrally connected together at their upper ends by a lateral V-shaped portion 8. The junctions of the upper ends of said leg portions 7 with the outer ends of the intermediate V-shaped portion 8 provide rounded loop or seat portions 9. The free or lower extremities of said leg-portions 7 are turned or bent back upon themselves to form eye-portions or hooks 10, disposed to 100 extend in a plane at right angles to the general plane of the connector link element. 105 110

- 2
- In assembling the main link elements and the connector link elements together to make up the novel bed-spring fabric, said main link elements are arranged in lateral rows, 5 in such numbers per row as may be necessary to provide a spring body of desired width. The said main link elements, as thus arranged, are so disposed that their eye-portions or hooks 5 are in lateral alinement. 10 The connector link elements are now assembled with the main link elements by threading a connector link element through the eye-portions 5 of adjacent leg portions 2 of a pair of adjoining main link elements, so that 15 said connector link extends between and interconnects one of the leg-portions 2 of one main link element with the adjacent leg-portion 2 of an adjoining main link element throughout the width of the fabric. When 20 thus assembled the eye-portions or hooks 5 seat themselves in the respective loop or seat portions 9 of said connector link elements. The members of one lateral row of main link elements having been thus interconnected 25 together by the connector link elements, the next lateral row of main link elements are connected with the leg-portions 7 of said connector link elements by threading the former through the eye-portions or hooks 30 10 of the latter, so that said eye-portions or hooks 10 of the leg-portions 7 of adjoining connector link elements seat themselves in the loop or seat portions 4 of the thus assembled next row of main link elements. The 35 operations of thus assembling alternate interconnected lateral rows of main link elements and connector link elements is carried on until a spring fabric of desired length is produced. In the spring fabric 40 thus produced the leg-portions 2 of the main link elements are interconnected and substantially longitudinally alined with leg-portions 7 of said connector links, thereby forming substantially continuous pairs of 45 parallel longitudinal strands running through the fabric, which are laterally interconnected at intervals by the respective V-shaped portions 3 and V-shaped portions 8 of the respective sets of link elements. 50 To finish off the longitudinal outer edges of the fabric thus built up, straight finishing links 11 having suitably formed hook portions 12 and 13 at their respective ends are interconnected with the outermost connector 55 link elements, as shown in Fig. 1. The ends of the fabric thus formed are provided with coupling loops 14 having hook portions 15 for engaging with the fabric at the termini of the respective parallel longitudinal 60 strands provided in the fabric as above described. The fabric is then mounted or suspended in a suitable supporting framework (not shown) by the usual helical springs 16 interconnected between said supporting framework and said coupling loops 14.

It will be apparent that the respective V-shaped portions 3 and 8 of the main and connector link elements by reason of their lateral extension and shape tend to provide for a lateral elasticity in the fabric, since weight or pressure, when applied to or brought to bear on the fabric, will tend to cause said V-shaped portions to stretch or straighten between the longitudinal strands in proportion to the amount of weight or pressure, and consequently the tendency of the fabric is to yield readily to the weight of the person or persons lying thereon in proportion to the downward thrust exerted by such weight, so that the fabric also tends to conform readily to the contours of the body, rendering the bed-spring exceedingly comfortable and restful as a body support. 75

It will also be apparent that the link elements per se are of simple design, requiring but comparatively few bends to produce the desired shape thereof; and due to the simplicity of shape comparative economy in the amount of wire required for their formation is attained. 85

Referring now to Figs. 3 and 4 of the drawings, I have illustrated a somewhat modified form of fabric which embodies, however, the principles and practical advantages sought by this invention as already 90 above mentioned. In this construction, the main link elements 17 are of general M shape, but the leg portions 18 thereof are inclined outwardly or divergent toward their lower free ends. The upper ends of 95 said leg-portions 18 are integrally connected together by the lateral V-shaped portions 19, the junctions of which with said leg-portions provide the rounded loop or seat portions 20. The free or lower extremities of 100 said leg-portions 18 are turned or bent back upon themselves to form eye-portions or hooks 21 at right angles to the general plane of the link-body. 105

In this modified form of fabric instead 110 of employing the small M-shaped connector links above described, I employ connector loops 22 having divergent legs 23 terminating in eye-portions or hooks 24 and like the loops 14 of Fig. 1. 115

In assembling this modified form of fabric, the main link elements 17 are arranged in lateral rows, in such mutual relation that eye-portions or hooks 21 of adjacent leg-portions 18 of adjoining link elements are brought side by side and laterally alined. The connector loops 22 are now threaded through the thus arranged eye-portions or hooks 21, so as to engage with 120 each connector loop 22 a pair of main links 17. The next lateral row of main links are threaded through the eye-portions or hooks 24 of the connector links, so that adjoining main links have their adjacent seat portions 20 respectively engaged with the respective 125 130

legs of said connector links. Finishing links 25 are interconnected between the longitudinally disposed outer rows of main links 17 to produce a straight finished edge or margin at each longitudinal side of the fabric. Helical springs 26 are connected with the ends of the fabric to resiliently suspend the same upon a suitable frame or support (not shown).

10 An inspection of Figs. 3 and 4 will clearly indicate that the above described modified form of spring fabric will provide for that lateral resiliency, flexibility or stretch which renders the fabric comfortable and restful 15 as a body support, in substantially the same manner as already set forth in connection with the first described form of fabric.

I claim:—

1. A wire fabric comprising a plurality 20 of main links having substantially parallel legs interconnected together by a V-shaped expansible portion at one end, said main links being arranged side by side in transverse rows, the main links of one row being 25 longitudinally aligned with the main links of adjacent rows, and a plurality of connector links, said connector links serving to mutually interconnect both transversely and longitudinally adjoining main links.

30 2. A wire fabric comprising a plurality of M-shaped main links arranged in rows

extending transversely of the fabric, and a plurality of small M-shaped connector links also arranged in rows extending transversely of the fabric intermediate adjoining rows 35 of said main links, said connector links being interconnected in staggered relation and disposition with the main links of adjoining rows thereof.

3. A wire fabric comprising a plurality 40 of comparatively large M-shaped links arranged side by side in rows extending transversely of the fabric, the free ends of said links having hook-portions, and a plurality of small M-shaped connector links, the free 45 ends of said connector links having hook-portions, the closed ends at the upper sides of said small M-shaped connector links being engaged respectively by the hook-portions 50 at the ends of adjacent large M-shaped links in one row while the hook-portions at the free ends of said connector links are engaged respectively with the adjoining closed ends of adjacent large M-shaped links 55 in the next row.

In testimony, that I claim the invention set forth above I have hereunto set my hand this 18th day of November, 1921.

JACUB SCHWARTZMAN.
